UNITED STATES PATENT OFFICE

2,483,324

CORN DRIER

Olaf J. Peterson, Zumbrota, Minn.

Application March 26, 1948, Serial No. 17,210

4 Claims. (Cl. 263—32)

1

This invention relates to a material drying chamber or kiln, adapted for drying or aging agricultural products, such as corn or the like, and has for its principal object to enable material to be thoroughly and completely dried in a minimum of time.

Another object of this invention is to provide for the thorough drying of the material and, at the same time, to obviate any possibility or tendency of flames or hot gasses entering the drying chamber and igniting or spoiling the material therein.

Another object of this invention is to withdraw from the drying chamber, the moisture, given off by the wet material and to selectively control the amount of moisture in the material and the variation of moisture therein.

Another object of this invention to be specifically herein enumerated is to provide a drying chamber, kiln or the like, which is simple in structure, economical to manufacture, and durable and reliable in operation.

A meritorious feature of this invention resides in the provision of a pair of inner and outer drums, the inner drum serving as a drying chamber, within which the material is placed, and the inner drum extending a suitable distance beyond the ends of the outer drum, so as to obviate the possibility of flames or hot gases entering into the inner drum.

Another important feature of this invention resides in the provision of longitudinal spacing baffle members disposed between the concentric drums, defining individual drying chambers or partitions.

Another important feature of this invention resides in the provision of an end extending stack, in communication with the drums, with the stack being vertically divided into sections, with dampers disposed in the sections, and an exhaust fan transversely mounted about the sections within the stack, so that the hot gases are withdrawn from between the concentric drums through one of the stack sections, while the other section serves as an exit for the moisture, from the inner drum or drying chamber.

These and ancillary objects and other meritorious features are attained by this invention, a preferred embodiment of which is set forth in the following specification and illustrated in the accompanying drawings, wherein:

Figure 1 is a vertical longitudinal sectional view of a drying kiln, for agricultural material and the like, constructed in accordance with the principles of this invention;

2

Figure 2 is a front elevational view of this invention;

Figure 3 is a transverse vertical sectional view taken substantially on lines 3—3 of Figure 1;

Figure 4 is a transverse vertical sectional view taken substantially on the plane of lines 4—4 of Figure 1;

Figure 5 is a fragmentary enlarged sectional view of a portion of the concentric drums, illustrating the means provided for spacing the drums apart and dividing the spacement section into chambers;

Figure 6 is an enlarged fragmentary sectional view of the means provided for conducting or conveying heated gases, between the concentric drums, as shown generally in Figure 1 of the drawings;

Figure 7 is a top plan view of this invention, and

Figure 8 is a fragmentary enlarged sectional view of the roller supports and the annular guide ring, circumferentially disposed on the outer drum, as shown generally in Figure 1 of the drawings.

Referring now more particularly to the drawings, wherein similar characters of reference designate corresponding parts throughout, there is shown a pair of longitudinally extending transversely spaced H-shaped base supports 12 and 14, upon which a drying kiln or the like, generally denoted by the character reference 10, and constructed in accordance with the principles of this invention, is seated and supported.

Supported on the longitudinally extending H-base beams 12 and 14 and transversely extending thereon are a pair of roller support brackets 16 and 18, respectively. The roller support brackets 16 and 18 comprise a cross-beam 20, having disposed on its terminating portions a pair of apertured ears 20 and 22, within which are journaled, by means of axle 24, a roller 26 having annular end flanges 28 and 30, thereby defining a medial guide-way 32.

It is to be noted that the roller support 16 is substantially lower than the roller support 18, thereby defining a tilted or inclined placement of the kiln 10.

An outer cylindrical drum 34 is rotatably supported upon the roller supports 26, by means of circumferentially disposed longitudinally spaced substantially H-shaped rollers 36 and 38, the rollers being received within the medial guide-way 32 of the rollers 26 and suitably supported therein. By providing a medial recessed guide-way 32 on the rollers 26, it can be seen that the

drum 34 is supported in secure placement and the tendency of the annular rollers 36 and 38 to move off of the rollers is obviated.

Suitably supported on the base support 12 by means of a U-shaped transverse bar 40, having depending lateral seat portions 42 and 44 which are bolted as at 46 to the supports is a motor 48, bolted as at 50 to the U-shaped bracket. The motor 48 is of conventional structure and description and has extending therefrom an armature shaft 52, upon which is suitably keyed a gear drive 54. An annular ring gear 56 is suitably secured on the circumference of the outer drum 34 and is engaged by the drive gear 54, thereby imparting rotation to the drum 34.

Concentrically disposed within the outer drum 34 is an inner or drying drum 60, which is suitably spaced from the outer drum 34, by means of longitudinally extending circumferentially spaced baffle beams 62, which define compartments 64, between the concentric cylindrical drums, for a purpose to be later described.

Suitably secured to the inner circumference of the drying drum or chamber 60 and extending longitudinally therein are angle beams 66 having one side secured to the interior of the drum, as by rivets or bolts 68.

With reference to Figure 1 of the drawings, it is to be noted that the inner drum or chamber 60 has its annular terminal portions 70 and 72 longitudinally extended beyond the terminating portions of the outer drum 34 for a purpose to be later described.

Positioned at the open end 70 of the inner drum 60 is a supply or intake chute 76, which is vertically supported in an upright position on the base beams 12 and 14, by means of legs 78 and 80, having lateral foot portions 82 and 84 which are suitably bolted, as at 86, to the base beams. The vertical terminating portions of the legs 78 and 80 are inturned and secured as by bolts or rivets 88 to the sides of the supply chute 76. Brace bars 90 are provided to brace or rigidify the extending nozzle or spout portion 92 of the supply chute 76, the discharge spout 92 terminating a spaced distance within the inner drying chamber 60.

The outer drum 34 is suitably spaced from the inner drum 60, at the terminating portion 70 of the inner drying chamber 60 by means of an annular stationary bearing ring 94, which is suitably received and supported on the outer circumference of the drying chamber and upon which the terminating portions of the outer chamber 34 are secured, as at 96.

Suitably supported on the extending base beam 12, as by means of substantially U-shaped transverse bar 100, having lateral foot portions 102, which are bolted by bolts 104 to the base supports, is an oil burner unit 106, of conventional structure and including an oil feed line 108 and a discharge nozzle 110. The discharge nozzle 110 is received within an intermediate conveying or conducting tube 112, the opposite end of the tube 112, with reference to Figure 6 of the drawings, being angularly bent and suitably received between the inner drying drum 60 and the outer drum 34, and is inserted within the permanent annular ring 94, the annular ring 94 being securely supported on the support bar 114, which is bolted as at 116 to the base beams 12 and 14.

Suitable means are provided whereby the heated gases, which are conveyed through the connecting tube 112 into the separate chambers or partitions 64, formed by the dividing baffle 62, between the inner and outer drums, and also, suitable means are provided whereby the mois-

ture, which accumulates within the drying chamber 60, coincident to the wet material within the interior of the drying chamber and the heat conveyed on the outer circumference of the drying chamber is withdrawn.

The means preferred comprises an end stack 120, which includes a spaced end shield 122, having a suitable chute opening 124 disposed at the end thereof, whereby the material may be provided an exit from the drying chamber 60 and may be conducted or conveyed to an endless bucket elevator, generally denoted by the numeral 126, which is disposed in spaced proximity to the discharge chute 124. One end 126 of the discharge chute is received within the lower portion of the transversely extending channel support 128, and the extending end 72 of the drying chamber 60 is seated thereon. The annular support 128 is bolted as at 130 to a transverse support base 132, the bearing support having a laterally extending portion 134, which forms an annular attaching lip received around the outer drum 36. Formed integrally with the ring 134 and extending vertically therefrom is a front portion 136 of the stack 120, the stack including the side wall 138.

Disposed within the stack 120 is a vertical partition 140, having its depending end angularly bent and seated loosely upon the extending end 72 of the drying chamber 60, the depending end 142 being formed integrally with the inner end 126 of the secured supporting annular ring, received around the extending portion 72 of the inner drying chamber 60. The vertical partition 140 defines a pair of vertical chambers 144 and 146, the chambers having a pair of butterfly dampers 148 and 150 suitably disposed therein and controlled by handles 152 which extend or protrude beyond the stack interior.

Transversely disposed within the stack 120 and positioned above the vertical compartments 146 and 144 is an exhaust fan 154, of conventional structure and having a bevel gear 156 secured on the extending portion thereof, in complementary engagement with a bevel gear 158, carried by a transverse shaft 160, which protrudes through the end wall 122 of the stack 120, suitable bearings or bushings 162 being provided on the shaft 160, the shaft 160 extending from the motor 162 of conventional structure and being driven thereby.

The motor 162 is suitably supported on the outside of the stack 120, on the end wall 122 thereof by an angular bracket 164, secured to the end wall 122 as by bolts 124, with a brace bar 166 being provided to rigidify the angle support.

In operation, a supply of material, such as corn or the like, is manually placed within the inlet chute 76 and is discharged into the drying chamber 60 by means of the discharge nozzle 92. The concentric drums 34 and 60 are suitably revolved, through the medium of the motor 48 and the gear drive 54 in contact with the annular ring gear 56, disposed on the outer circumference of the outer drum 34, the outer drum 34 being guided in its revolutions, by means of the annular tracks 36 and 38, which are received in the rollers 26.

As the outer drum 34 revolves, the inner drum revolves unitarily therewith, with the material being suitably agitated or shaken up by means of the agitating members 68, which radially project from the inner circumference of the drying chamber 60, towards the inner portions thereof.

As the concentric drums revolve, with the material inside, an oil burner unit 106 is placed

in operation, and the hot gases are conveyed through the conducting tube 112 into the individual longitudinal compartments 64 disposed between the concentric drums, and thereby, the outer surface of the drying chamber 60 is suitably heated and accordingly, the material housed therein is responsively dried.

Due to the extension of the inner drum 60 at both its ends, which are positioned beyond the terminating portions of the outer drum 34 and due to the vertical partitioning of the stack 120, which partition seats upon the outer extremity of the drying chamber 60, the hot gases which are projected through the compartment 64 are drawn off through the separate vertical compartment 144, through the medium of the exhaust fan 154 and controlled in their exit by butterfly damper 150. Thus, it can be seen that as the hot gases are never in contact with the extreme ends of the inner drying chamber and accordingly, it is not possible for the material within the drying chamber to become ignited due to contact with the hot gases or flames.

The adjacent vertical compartment 146 in the stack 120 serves to provide an exit for the moisture given off from the produce in contact with the heated drum and the moisture is suitably exhausted from the inner drum through the compartment 146, controlled by the damper 148, through the medium of the exhaust fan 154.

The dried material is suitably discharged through the discharge spout or chute 124, which conveys the material to an endless bucket elevator 126, disposed in vertically spaced proximity thereto.

It is to be noted that the variation of moisture removed from the corn may be suitably controlled by the vertical adjustment of the drying drum within the outer drum, by raising or lowering one end thereof, and accordingly, regulating the heat and the flow of the material therethrough.

Thus, it can be seen that there is provided a drying kiln, which will accommodate any desired amount of material and which will conveniently and easily, in a minimum of time and with a minimum of effort expended, dry the material, at any desired degree, and at the same time, remove any possibility that the material may become ignited through contact with the hot gases or flames.

Since many other modifications and purposes of the invention will become apparent to those skilled in the art, upon a perusal of the foregoing specification, in view of the accompanying drawings, it is to be understood that certain changes, not amounting to invention, may be effected thereon, without constituting a departure from the spirit of the invention and within the scope of the appended claims.

Having described the invention what is claimed as new is:

1. A material drying kiln comprising a pair of base supports, rollers mounted on said supports, a prime mover, having a gear drive, mounted on said supports, a pair of inner and outer drums, annular guides received on the circumference of the outer drum and seated in said rollers, an annular ring gear disposed on the circumference of the outer drum and actuated by said drive gear, a supply chute supported adjacent an end of the drums, a series of longitudinal agitating elements carried by said inner drum, a blower burner unit disposed under said supply chute, a connecting tube attached to said burner and received be-

tween said drums, a discharge chute carried by said inner drum, an end shield covering said drums, an exhaust stack supported by said end shield and the outer drum, said stack being vertically divided into sections, dampers supported in said sections, and an exhaust fan operatively disposed in said stack.

2. A material drying kiln comprising a supporting base, rollers rotatably mounted on said base, a prime mover mounted on said base, a pair of concentrically disposed spaced inner and outer drums revolvably supported on said base and driven by said prime mover, said inner drum extending beyond the outer drum at the opposing ends thereof, a supply means disposed at one end of the drums for discharging material into the inner drum, a burner unit disposed under said supply means, means for conducting hot gas from the unit between the drums, a shield disposed at the discharge end of the inner drum, a discharge chute carried by said shield, a stack vertically mounted on the inner and outer drums at the discharge end, a vertical partition in said stack defining a passage for the inner drum and a passage for the outer drum, means disposed in said stack for exhausting the gases from between the drums and the moisture from the inner drum, control means disposed in each of the passages.

3. A material drying kiln comprising a horizontally positioned supporting base, a prime mover mounted on said base, a pair of concentrically disposed cylindrical drums rotatably mounted in an inclined plane on said base and driven by said prime mover, the opposing ends of said drums being open and said inner drum having its ends extended beyond the ends of the outer drum, spacing means between said drums, a supply means disposed at one end of the drums for discharging material into the inner drum, a burner unit disposed below the supply means, means for conducting hot gas from the unit between the drums, a shield covering one end of the inner drum, a discharge chute carried by said shield, a stack vertically disposed at the discharge end of the drums and formed on the shield and mounted on the outer drum, a vertical partition in said stack defining a passage for the inner drum and a passage for the outer drum, an exhaust fan disposed in said stack above the partition, dampers in said passages and agitating means disposed in said inner drum.

4. A material drying kiln comprising a horizontally positioned supporting base, a prime mover mounted on said base, a pair of concentrically disposed cylindrical drums rotatably mounted in an inclined plane on said base and driven by said prime mover, the opposing ends of said drums being open and said inner drum having its ends extended beyond the ends of the outer drum, spacing means between said drums, a supply means disposed at one end of the drums for discharging material into the inner drum, a burner unit disposed below the supply means, means for conducting hot gas from the unit between the drums, a shield covering one end of the inner drum, a discharge chute carried by said shield, a stack vertically disposed at the discharge end of the drums and formed on the shield and mounted on the outer drum, a vertical partition in said stack defining a passage for the inner drum and a passage for the outer drum, an exhaust fan disposed in said stack above the partition, dampers in said passages and longitudinally extending circumferentially spaced agitating

bars mounted on the inner surface of the inner drum.

OLAF J. PETERSON.
